UNITED STATES PATENT OFFICE.

EUCLID I. LA CHAPELLE, OF BEVERLY, MASSACHUSETTS.

LASTING-MACHINE.

1,085,385.

Specification of Letters Patent.

Patented Jan. 27, 1914.

Application filed August 21, 1912. Serial No. 716,225.

To all whom it may concern:

Be it known that I, EUCLID I. LA CHAPELLE, of Beverly, in the county of Essex and State of Massachusetts, have invented 5 certain new and useful Improvements in Lasting-Machines, of which the following is a specification.

This invention relates to lasting machines and more particularly to such machines having a plurality of lasting grippers and fastening inserting devices.

This invention is illustrated in the drawings as applied to the United States patent to Ronald McFeely, No. 663,777, dated Dec. 15 11, 1900. This machine is selected as a type of the lasting machines to which this invention may be applied and it is to be understood that the invention may equally well be applied to various other lasting machines.

20 It is well known to those skilled in the art of making shoes, that the most satisfactory shoe is obtained by securing the upper to the sole with the tip-seam diagonally disposed to the longitudinal median line of the shoe. 25 A machine for lasting shoes in this manner is shown in the patent to Arthur Bates, No. 1,006,456, dated October 24, 1911.

One object of the present invention is to provide new and improved means for securing the above described diagonal position of the tip-seam and setting the upper to the wood of the last. This feature is carried 30 into effect by constructing the grippers which engage the marginal portion of the upper near each end of the tip-seam so that the grippers at one end of the seam are stopped and held in a predetermined position lengthwise of the last at one side while the seam is set diagonally of the last by the 35 movement of the grippers. In some cases I may impart the foredraw movement to each of the grippers so as to strain the upper toward the toe of the last as is usual. In such a case I would set the stopping 40 means prior to the foredraw movement to positively stop the grippers at one side of the last to set the tip-seam, as has been described. The devices for positively stopping the foredraw movement of the grippers are 45 adjustable so that the degree of the angle of the tip-seam and the point at which the seam is held toward the toe of the last may be varied according to the different styles of lasts. One end of the tip-seam being thus 50 held at a predetermined position at one side of the last, brings about uniformity in

length of tip at that side of the last, provided that the toe of the last is set at each operation against the toe-end gripper, by the operator.

60 In lasting a shoe by hand, some workmen first pull the toe-end of the vamp or of the tip, as the case may be, and then move the vamp and its seams laterally of the last, toward the big toe-side, and they then secure 65 the toe-end of the upper to the last. They next pull the upper at the little toe side of the last at sufficient distance to allow for the lasting tacks to be inserted properly. They then fasten the vamp to the last, or to 70 the sole on the last, as the case may be. They next strain from the big toe side of the last upwardly and forwardly and finally apply fastenings to that side of the last. It has been found that it is productive of better results 75 and easier for the workman to strain the upper mostly from the big toe side of the last as above explained.

80 The general object of this invention is to provide a lasting machine producing uniformly lasted shoes, whether or not one side of the upper has been pulled more than the other side. It is also an object of this invention to provide means in a lasting machine for lasting a shoe in a manner corresponding to the hand operation above explained. 85 To the accomplishment of this object a further feature of the invention comprises means for causing the grippers on one side of the upper, preferably the outside or little toe side, to pull or hold without pulling the upper toward the bottom of the last so as to provide the desired margin of upper to be secured to the last. The final straining and setting of the upper is done by the grippers 90 on the inside, or big toe side of the last. An adjustable stop is provided for each gripper to limit the distance through which it moves to pull the upper in readiness to be fastened to the last. Ordinarily the stops 95 controlling the grippers at the big toe side of the last are rendered inoperative so that the upper is strained at that side of the last against the usual spring tension of the grippers. In some instances, however, it is desirable that the stops on both sides of the 100 last shall be operated so that there will be a positive limit to the movement of the grippers at each side of the last. Uniformity in length of tip will then result as both ends 105 of the tip-seam are thus set at predetermined 110 positions lengthwise of the last.

2
 In some cases I set the tension of the grippers per actuating levers so that the grippers do not reach the predetermined limit of their movement at a single operation of the machine. The hand levers controlling the grippers shown in the aforementioned McFeely patent are then manually operated to complete the movement of the grippers to their positive stopping point. It is desirable that the final pulling movement of the upper shall be slow on some styles of lasts in order to avoid tearing the vamp or the lining.

15 The updraw straining movement of the grippers is of greater importance than the foredraw movement and in some cases, the foredraw movement may be dispensed with, as for instance, when an upper has been pulled lengthwise prior to the pulling-over operation proper.

20 The two features of this invention hereinbefore described may be however very conveniently combined as is illustrated in the drawings. These features in their simplest form would be exemplified by a single pair of grippers at or near each end of the tip-seam of an upper on a last. The grippers at the little toe side of the last having a limited movement and the grippers at the big toe side having a movement which may or may not have a positive limit to set the upper to the lines of the last and a foredraw movement to move the tip-seam about an axis passing substantially through the other grippers that have already been moved to a predetermined position. The two grippers described may be sufficient, in some cases, to properly last a shoe.

25 The strain required to properly last an upper as contemplated by this invention is considerably less than that required by the machines at present in use. Another advantage in the manner of operation of this invention is apparent when used on welt 30 shoes. In making welt shoes it is customary to secure an insole to the last with the periphery of the big toe side of the forepart of the sole coincident with the corresponding part of the last, thus allowing any surplus width of the sole to project over the bottom of the last at the little toe side. In the pulling over machines heretofore employed the upper on each side of the last has been drawn upwardly. A projecting edge of the insole would then be bent away from the bottom of the last by the friction of the vamp against the sole edge during the updraw movement of the grippers. At the welt sewing operation the needle would then be liable to engage the edge of the insole, so that the stitches would, in some instances, pass through the edge of the insole after passing through the between substance. In the present invention, the final strain of the upper is preferably at the big toe side of

the last where there is no projecting insole edge. Thus the edge of the insole at the little toe side is bent by the friction of the vamp, toward the last and against its side out of the path of the needle during the welt sewing operation. This is made possible by the grippers at the little toe side of the last yielding under the influence of the grippers at the big toe side of the last at the end of their straining movement on the vamp. 75 This advantage may also be of value in other kinds of shoes wherein the edge of the sole projects over the edge of the last at one side.

80 As has been stated, the general object of this invention is to secure uniformity in lasting, and for this reason, positive stopping means are always preferable whenever the nature of the work will permit. It is of advantage, in some cases, to pull an upper to indefinite points at both sides of the last 85 and to have positive stopping means to hold the grippers at one side of the last from movement toward the last under the influence of the grippers having greater pulling power at the other side of the last. 90

95 A novel and important feature of this invention resides in the provision of means to render the stopping means operative or inoperative as may be desired. The stopping means shown in the drawings are the hooks 26. These may be rendered inoperative by turning the hooks away from the path of the gripper actuating levers 6 or 7 which will allow the grippers at both sides of the last to pull the upper to an indefinite 100 point. After the gripper actuating lever at one side of the last has passed the hook 26 while it is in operative position, the hook may be turned so as to lie beneath the lever and thereby prevent it from being drawn 105 toward the last by the pull of the grippers at the opposite side of the last transmitted through the upper. It is apparent that the hook should be turned under the lever having the lesser pulling power. In this manner, a predetermined stopping point is provided to limit the movement of the grippers toward the last after the upper has been pulled. 110

115 In some cases it may be desirable to employ the hooks 26 to hold the grippers at a predetermined distance from the last without exerting any pull on the upper by the grippers so held. In this instance, the operator would move the grippers at one 120 side of the last to a predetermined distance therefrom by moving the gripper actuating levers 6 or 7 as is described in the aforementioned patent to McFeely. The upward movement of the levers causes the grippers 125 to close automatically on the upper. After the operator has moved the grippers through a sufficient distance to cause them to engage the upper, the hook or hooks at that side of the last can be turned, as has been described, 130

so as to hold the grippers a positive distance away from the last at that side.

Another novel and important feature of this invention relates to means for supporting the last which may be laterally inclined to the plane of the upper engaging devices, which as herein described, are the grippers.

I provide supports at each side of the last with means for independent adjustment toward and from the last. The supports may be actuated at any time. In some cases, the supports are preferably actuated after the upper has been strained so as to alternately move the sides of the last in the upper to secure a better adjustment of the upper to the lines of the last. These adjustments of the supports are necessary only in special cases where vamps or vamp linings do not properly fit the last. I have also found it desirable to provide means for adjusting the grippers toward and from the last and for holding them in adjusted positions as will be hereinafter set forth.

When a lasting machine includes means for supporting the last against lengthwise movement, the toe gripper may be dispensed with. Supporting means of this character are set forth in a United States Patent No. 950,179, dated Feb. 22, 1910, issued to the present applicant. The advantages of these features and such others as may hereinafter appear will be apparent to one skilled in the art from the following description and accompanying drawings, in which:—

Figure 1 is a side elevation of the lasting machine shown in the United States patent to Ronald F. McFeely, No. 663,777, dated Dec. 11, 1900, having the preferred form of the present invention embodied therein; Fig. 2 is a side elevation of the opposite side of the machine to that shown in Fig. 1; Fig. 3 is a detail showing the means for stopping the straining movement of the grippers; Fig. 4 is a detail in section of the means for guiding the toe grippers and for permitting a lateral movement thereof; Fig. 5 is a sectional detail showing the means for adjusting the support of the side grippers to be hereinafter explained; Fig. 6 is a perspective of a shoe which has been lasted in accordance with the preferred form of the present invention; Fig. 7 is a bottom view of the last supporting means; and Fig. 8 is a sectional detail showing particularly the means for adjusting the last supporting means.

The general construction and operation of the machine illustrated in the drawings may be identical with the construction shown in the patent to McFeely. A toe gripper 1 is carried by a support 2 (Fig. 4) and adapted to be operated in the usual manner. Side grippers 3 and 4 are carried by guides 5 and actuated to pull the upper through suitable connections to levers 6 and 7. These levers

are actuated to move the side grippers from an eccentric cam 8 which is constructed to move the levers through springs 9 and 10 at each side of the machine, as is set forth in the patent hereinbefore referred to.

As described in the patent the springs 9 and 10 may be adjusted to vary their tension by means of thumb nuts 9' and 10'. In the use of my invention I adjust one of the springs by means of its nut to preferably give a greater strain on one side of the shoe than upon the other. It is usual for the operative to adjust the springs so as to produce equal strains on each side of the vamp. In the general use of my invention, I find it desirable to have the greater spring tension on the gripper at the big toe side of the last for welt and turn shoes, and at the little toe side of the last for McKay shoes. A greater strain is also secured upon the upper on one side of the shoe than upon the other by an appropriate adjustment of the last supporting devices hereinbefore mentioned. These devices engage the last near the sides. A third foot 13 is provided to engage the forepart of the last near the toe. In order to produce a greater strain upon one side of the upper than upon the other, the feet 11 and 12 are independently adjustable so as to hold one side of the last lower than the other. The feet 11 and 12 are both mounted in the same manner, so that but one of these need be described. Referring to Fig. 8 the foot 11 is pivoted on one end of the lever 14 which is in turn pivoted at 15 on a plate 16. The foot 11 may be adjusted to hold the bottom of the last nearer to or farther from the grippers by moving the lever 14.

A lock is provided to secure the lever in its adjusted position. The lock may consist of a latch 17 pivoted on the lever 14 and having one end constructed to engage notches 18 in a segment 19 which is fixed upon the plate 16.

The toe engaging foot 13 is carried on the end of an arm 20 which has the usual adjustments well known to those skilled in the art. It is at present the custom to provide a rigid toe engaging foot. In the present invention it is desirable that the foot shall be capable of a turning movement so that it may retain its work engaging surface at all times parallel to the bottom of the last. To this end, the foot 13 is freely pivoted on a stud 21 so that it is capable of rocking in accordance with the angular position of the last.

The feature of the invention, above described will secure desirable results in the lasting of uppers that do not properly fit the last, as hereinbefore stated. The quality of the work is greatly improved in some cases by the use of certain adjusting and controlling devices for the grippers. In

some instances it is desirable that the side grippers shall be adjusted toward or from the work and it is also desirable that the grippers at each side of the last shall be capable of independent adjustment. I secured this adjustment by lengthening the connection between the grippers 3 and 4 with their actuating levers 6 and 7. As illustrated in the drawings the connection 10 consists of screw threaded studs 23 carried by the levers 6 and 7 and studs 22 secured to the gripper bars. Each pair of studs is connected by a turn buckle. It is apparent that the rotation of the turn-buckle will 15 move the grippers toward or from the work. In order that the gripping action of the pincers of the side grippers 3 and 4 may occur at the proper time, mechanism is provided for adjusting the point of support of 20 the side grippers in accordance with the adjustments of the turn-buckle 24. This is illustrated in Fig. 5, which also shows a section through the point of support of one 25 of the grippers. The stud 22 is mounted to slide in a collar 35. The position of the collar 35 determines the time at which the pincers will open or close. The roller is provided with ears 36 which are engaged above and below by set screws 37 and 38. 30 A plurality of these screws may be provided, when necessary, to form a path for the collar. It is apparent that the screws on one side of the ears 36 may be loosened and the screws on the other side tightened 35 so as to cause the grippers to be actuated at the same time on both sides of the last. It will be necessary to readjust the collar 35 whenever one of the turn-buckles 24 is adjusted, in order that the timing of the grippers may be simultaneous. This feature is 40 most desirable for shoe uppers that are very small for the last.

It has been found desirable to pull the upper toward the toe, at the sides of the last, at the same time it is drawn over the last. 45 Machines have been built in which the upper was pulled toward the toe during the lasting operation, but these machines have not been capable of pulling over the upper as well as a skilled hand operator. The reason for 50 this is that there is more slack material at the shank of the big toe side of the shoe than there is at the other side. The most skilled hand lasters take up some of this 55 fullness by drawing the side of the tip or the vamp more toward the toe at the big toe side of the last than what they do at the other side. This not only gives a better lasted shoe, but improves the appearance of 60 the shoe by giving the tip-seam a slight slant toward the toe at the big toe side of the shoe. An important feature of this invention comprises means for accomplishing this result in a better manner than hereto- 65 fore accomplished.

It is old to provide cams indicated at 25 to draw the upper toward the toe on each side of the last. In the machine of the present invention I contemplate a provision of means for positively stopping at predetermined points the pulling movements, toward the toe and toward the bottom of the last. This is preferably accomplished by providing means for adjusting the stopping means prior to the pulling movement upon 70 the upper at a predetermined point, for stopping the movement of one of the levers 6 or 7. Two hooks 26 are secured by their screw threaded shanks in a fixed portion at 27 of the machine frame. The hooks are 75 provided with knurled heads 28 by which they may be adjusted in their supports 27 and also to provide means for turning one of the hooks away from its coöperating gripper actuating lever so that the lever 80 may move freely past the hook, as is shown on the right of Fig. 3. In this figure the upward movement of the lever 6 will be stopped while the other lever continues to the full limit of its motion. The point at 85 which the motion of the lever is stopped may be varied by turning the hook in the support 27 and then locking it in its adjusted position by a set screw 29. As shown in the drawings, the lever at the little toe 90 side of the last is stopped, while the lever at the other side passes the hook unaffected.

The cams 25 controlling the grippers at the sides of the last, as shown in the drawings, have two distinct motions or paths. 100 The first cam motion is straight upwardly. The second motion is upwardly and forwardly. I preferably adjust the stopping means at the little toe side of the last to stop the grippers at that side of the last, before 105 the start of the second motion, for imparting a foredraw movement to the grippers.

When the upward movement of one of the grippers is stopped the foredraw is of course also stopped, while the movement toward the toe on the other side continues. It is also evident from the foregoing description that the updraw movement of the grippers, at one side of the last, will be longer than the other and will have greater straining power. 115 In the operation of this machine I prefer to have the excess length of the pull and strain at the big toe side of the last, so as to move strain, and set the upper and its seams more toward that side of the last, than toward the 120 other side.

The toe grippers with the tip should move slightly sidewise of the last under the influence of the side grippers, at one side of the last. It is desirable that the toe gripper 1 125 shall be capable of a slight lateral movement in order that it may not retard the action of the side grippers, or exert torsional strain on the vamp. To this end the casing 30 is provided at its upper end with a collar 31 130

which is carried in a relatively large hole, 32 in the support 2 in which it is normally centrally positioned by two plungers 33. The plungers are supported in suitable pockets in the support 2 and are pressed toward one another by springs 34. It is obvious that when the strain on both sides of the vamp and tip are equal there will be no tendency of the toe gripper to move toward one side or the other, but when the pull on one side of the vamp and tip exceeds the pull on the other side there will be a strain on the toe grippers toward the side having the greater pull. With a toe gripper constructed as has been described, the pull on the tip, or upper at the side of the last will produce a slight lateral movement of the toe grippers without interfering with the continued strain of the side of last grippers.

Fig. 6 shows an ordinary upper which has been strained and set over a last *x* and attached to a sole *y*, by my improved machine. The tip-seam at the point *a* has been drawn toward the toe more than the tip-seam at the point *b*. This figure also shows a greater portion of the vamp strained and set over on the bottom of the last at the big toe side part of the last than on the other side.

Having described the preferred embodiment of my invention, what I claim as new and desire to secure by Letters Patent is:—

1. A lasting machine, having, in combination, means for straining an upper over a last at the sides and at the toe-end, means for stopping the straining movement at a predetermined point at one side of the last, means to permit a greater straining movement at the other side of the last and means to allow a lateral movement of the straining means at the toe-end of the last under the influence of the straining means at one side of the last.

2. A lasting machine, having, in combination, means for pulling an upper over a last, means for automatically stopping the pulling movement at predetermined points, means for opening the grippers, means for turning the upper toward the bottom of the last and means for applying fastenings to secure the upper in lasted condition after said pulling means have stopped at said predetermined points.

3. A lasting machine, having in combination automatic power actuated means for straining an upper over a last, means for supporting the last, means for relatively adjusting the sides of the supporting means to vary the lateral angle of the last and automatic power actuated means for moving the supporting means during the straining movements on the upper.

4. A lasting machine, having, in combination, means for straining an upper over a last, means for adjusting the straining means toward and from the upper, means for holding the straining means in adjust-

ed positions and means for limiting the straining movement of the straining means.

5. A lasting machine having, in combination, grippers for pulling an upper on a last, actuating means to impart a reciprocating movement to the grippers, and stops adjacent the path of movement of the gripper actuating means constructed to be positioned with relation to said actuating means in the path of movement of the actuating means to limit the movement of said means toward the last and constructed to be positioned relative to the actuating means so as to limit the movement of said means away from the last.

6. A lasting machine having, in combination, grippers for pulling an upper at the sides of a last, means adapted to hold the grippers at one side of the last at a predetermined distance from the last after the upper has been engaged by the grippers, and means for pulling the upper by the grippers at the other side of the last against the side thus held, said holding means being capable of assuming an inoperative position during the movement of the grippers away from the last and an operative position during the movement of the grippers toward the last.

7. A lasting machine having, in combination, grippers, actuating devices to move the grippers toward and from the last, stops to limit the movement of the grippers said stops being adapted to be positioned in one or the other of two positions in relation to the grippers so as to limit the movement of the grippers in either direction, substantially as described.

8. A lasting machine having, in combination, means for pulling an upper at opposite sides of a last through unequal distances, means adapted to be positioned to hold the pulling means having the lesser pulling movement against the strain of the pulling means having the greater pulling movement, and means adapted to lock said holding means as positioned by the operator.

9. A lasting machine having, in combination, means for pulling an upper at opposite sides of a last with unequal strain, means adapted to permit the operator to move the pulling means away from the last, and means adapted to be positioned to hold the pulling means having a lesser straining power against the strain of the pulling means having the greater straining power.

10. A lasting machine, having, in combination, grippers adapted to engage an upper on a last, means, under control of the operator, whereby the last may be moved intermittently into the upper, and means whereby the said means, under control of the operator, may be held in adjusted position after the movement of the last into the upper.

11. A lasting machine, having, in combination, a plurality of grippers adapted to engage an upper on a last, automatic means to move the last into the upper, and additional means, under control of the operator, whereby the last may be moved into the upper after the automatic actuation of the means to move the last into the upper.
12. A lasting machine, having, in combination, grippers adapted to be positioned at opposite sides of a last to engage an upper on the last, means, under control of the op-

erator, whereby the last may be moved at one side of the upper, and means, under control of the operator, whereby the last may be held as finally positioned into the upper before the application of fastenings to hold the upper in lasted condition.

In testimony whereof, I have affixed my signature, in presence of two witnesses.

EUCLID I. LA CHAPELLE.
